[57] CLAIM

The ornamental design for a handboard for body surfing, as shown and described.

DESCRIPTION

FIG. 1 is a top, front and left side perspective view of a handboard for body surfing showing my new design; FIG. 2 is a right side elevation view thereof, the left side being a mirror image of the right side as shown;

FIG. 3 is a front elevation view thereof;

FIG. 4 is a top plan view thereof;

FIG. 5 is a bottom plan view thereof; and,

FIG. 6 is a rear elevation view thereof.

The straps in FIGS. 2, 3, 4, and 6 are shown broken away for convenience of illustration.

FIG. 1

FIG. 2

FIG. 3

FIG. 4

FIG. 5

FIG. 6

UNITED STATES PATENT AND TRADEMARK OFFICE
CERTIFICATE OF CORRECTION

PATENT NO. : Des. 329,633

DATED : September 22, 1992

INVENTOR(S) : Rogers, Jr. Michael

It is certified that error appears in the above-identified patent and that said Letters Patent is hereby corrected as shown below:

Title page, item (76):
